UNITED STATES PATENT OFFICE.

NAPOLEON LE BLANC, OF KANSAS CITY, MISSOURI.

WASH-STAND.

SPECIFICATION forming part of Letters Patent No. 268,502, dated December 5, 1882.

Application filed July 10, 1882. (No model.)

To all whom it may concern:

Be it known that I, NAPOLEON LE BLANC, of Kansas City, in the county of Jackson and State of Missouri, have invented certain new and useful Improvements in Wash-Stands; and I do hereby declare that the following is a full, clear, and exact description of the invention, which will enable others skilled in the art to which it appertains to make and use the same, reference being had to the accompanying drawings, which form a part of this specification.

Figure 1 is a perspective view of my improved wash-stand, showing the same folded out from the wall. Fig. 2 is a side view showing the same folded to the wall, and Fig. 3 is a plan view.

Corresponding parts in the several figures are denoted by like letters of reference.

This invention relates to an improved adjustable wash-stand, adapted especially for the use of barbers in attending to their customers; and it consists in the construction and arrangement of the same, which will be hereinafter fully described, and particularly pointed out in the claims.

In the drawings hereto annexed, A represents a crane or bracket hinged to the wall of the shop or room where the device is to be used, so as to be capable of being swung in toward the wall when so desired. The crane A has a curved arm, B, to the outer end of which is hinged a ring, C, in which a suitably-constructed wash bowl or basin, D, is set, substantially as shown in the drawings. The back 35 of the wash bowl or stand is provided with faucets E for hot and cold water, which said faucets are connected by flexible pipes F with suitable fixtures or supplies of any kind. From the bottom of the bowl extends a flexible waste-40 pipe, G, leading to the drain.

The pipes F G may be of leather, india-rubber, or of any suitable material, and any de-

sired construction which may be deemed suitable and convenient.

In operation, when the wash-stand is swung 45 in to the wall, as in Fig. 2, in which position the ring C, holding the wash-bowl, is accommodated in the curved arm B, thus enabling the bowl to be swung close to the wall, it may be conveniently used for all ordinary purposes, 50 such as wetting sponges and towels, washing hands, and for a variety of other uses. For washing or shampooing the head, the wash stand or bowl may be swung out to the position shown in Fig. 1, thus bringing it to a convenient 55 position for the operator, as well as for the person whose head is being treated.

Having thus described my invention, I claim and desire to secure by Letters Patent of the United States—

1. The combination, with a hinged bracket or crane having curved arm B, of a wash bowl or basin mounted in a ring hinged to said curved arm, as set forth.

2. The combination of the hinged bracket 65 or crane, the wash bowl or basin mounted in a holder hinged to the curved arm B of said crane, and flexible pipes connecting said wash-bowl with a suitable water-supply and waste-pipe, as set forth.

3. The combination and arrangement, as described, of the crane or bracket A, having curved arm B, the hinged ring or holder C, the bowl or basin D, having faucets E, and the flexible pipes F G, as and for the purpose 75 set forth.

In testimony that I claim the foregoing as my own I have hereto affixed my signature in presence of two witnesses.

NAPOLEON LE BLANC.

Witnesses:

S. A. WILLARD,
JOHN H. SPIKER.
